TO ARTHUR CROXFORD, OF SALT LAKE CITY, UTAH

SIGNALING DEVICE FOR VEHICLES

Application filed November 7, 1930. Serial No. 494,126.

My invention relates to and has for a purpose the provisions of a signaling device preferably although not necessarily in the form of a human figure having movably mounted arms constituting signal members, and embodying mechanism of simple and substantial construction, which in the applied position of the figure at the rear window of a vehicle, is operable automatically in response to checking of the vehicle's forward motion, to actuate the arms and move the latter momentarily from a normal lowered or non-signaling position to a raised or signaling position, thereby providing a visual indication for caution on the part of the driver of a following vehicle in order to avoid a collision.

I will describe only two forms of signaling device for vehicles embodying my invention, and will then point out the novel features thereof in claims.

In the accompanying drawings:

Figure 1 is a view showing in rear elevation, one form of signaling device for vehicles, embodying my invention.

Figure 2 is a vertical sectional view taken on the line 2-2 of Figure 1 and looking in the direction of the arrows.

Figure 3 is a view similar to Figure 1 and showing a second form of signaling device embodying my invention, and

Figure 4 is a view in side elevation of the form of my invention shown in Figure 3.

Referring specifically to the drawings and particularly to Figures 1 and 2, this form of my invention comprises a flat body of cardboard, hard rubber or other suitable material, having the configuration of a human figure 10 preferably simulating a uniform traffic officer, the arms 11 and 11^a of the figure being movable and pivotally mounted thereon to occupy either the lowered or non-signaling position shown in full lines in Figure 1 or the raised or signaling position shown in broken lines. If desired, the arms on their front sides may be provided with suitable legends such as "please stop" (not shown).

In the present instance the arms are secured to stub shafts 12 and 12^a journaled

in the shoulder portions of the figure and provided with lateral extensions constituting levers 13 and 13^a. The free ends of the arms terminate in eyes 14 and 14^a to which are connected one of the ends of cords 15 and 15^a respectively, the other end of the cords being connected to the cross bar 16 of a yoke 17, the legs 18 of which are provided at their free ends with eyes 19 receiving a pin 20 of U-shape driven into the figure 10.

The cross bar 16 of the yoke 17 carries a weight 21 in the form of a ball and co-acts therewith in forming a weighted member which by means of the pin 20, is pivoted or suspended on the figure 10, to the end that upon swinging movement of the yoke under the action of the weight, from the normal position shown in full lines in figure 2 to the other extreme position shown in broken lines, a sufficient pulling movement will be exerted upon the cords 15 and 15^a for them to coact with the levers 13 and 13^a in moving the arms 11 and 11^a from lowered to raised position.

The cords are passed through the opening formed by a brad 22 driven into the figure 10 and also through the opening formed by the U-shaped pin 20 so as to be guided and maintained against displacement.

The device as above described is preferably supported within the body of an automobile at the rear window W thereof, so as to be visible through the window from the rear of the vehicle. To this end a suction cup 23 of elastic rubber is secured to the front of the figure adjacent the feet portion thereof, and when applied to the window W as shown in Figure 2, supports the device in a fixed and upright position parallel to the plane of the window and sufficiently spaced from the latter to provide clearance for the movement of the arms between the Figure 10 and the window.

The operation of the device is as follows:

With the device applied as shown in Figure 2 and the automobile in forward motion as indicated by the arrow A, the arms 11 and 11^a and the weight 21 will occupy the lowered positions shown in full lines

in Figures 1 and 2, under the action of gravity. However upon checking the forward motion of the vehicle, the inertia of the weight will cause the latter to momentarily swing the yoke 17 outwardly from the figure or in the same direction as the vehicle's forward motion, thereby exerting a pull upon the cords 15 and 15^a to momentarily move the arms to the raised position shown in Figure 1, thus serving to indicate to the driver of a following vehicle, the necessity for caution in order to avoid a collision.

Reference will now be had to Figures 3 and 4 wherein I have shown another form of my invention embodying a figure 10^a similar to the figure 10, having arms 24 and 24^a fixed to stub shafts 25 and 25^a journaled in the shoulder portions of the figure 10^a and having secured thereto bevel gears 26 and 26^a respectively. These gears constantly mesh respectively with other bevel gears 27 and 27^a fixed on the ends of a rock shaft 28 journaled in bearings 29 secured to the rear side of the figure.

The rock shaft 28 is provided medially with a lateral extension in the form of a rod 30 to the free end of which is secured a weight 31 in the shape of a metallic ball. Under the action of the weight 31 the arms 24 and 24^a occupy the lowered position shown in Figure 3 when the weight occupies the lowered position shown in Figure 4. Upon swinging of the weight outwardly to the position shown in broken lines in Figure 4, it will be clear that through the medium of the pairs of bevel gears, the arms will be moved to the raised position shown in broken lines in Figure 3. To definitely limit the raised position of the arms, at least one of the bevel gears has its teeth mutilated at a predetermined location so as to co-act with its mating gear in limiting rotation of the shaft 28.

This form of my invention is applied to a vehicle in the same manner as the form shown in Figures 1 and 2 so that the inertia of the weight 31 will cause the latter to momentarily raise the arms 24 and 24^a when the speed of the vehicle is checked.

Although I have herein shown and described only two forms of signaling device for vehicles embodying my invention, it is to be understood that various changes and modifications may be made therein without departing from the spirit of the invention and the spirit and scope of the appended claims.

I claim:

1. A signaling device comprising a figure having arms, stub shafts journaled in the figure and to which the arms are secured, gears fixed to the stub shaft, a rock shaft journaled on the figure, other gears fixed to the rock shaft and meshing with the first

mentioned gears, and a weighted member projecting from the rock shaft for actuating the latter to move the arms from lowered to raised position or vice versa according as the weighted member swings to one extreme position or another.

2. A signaling device comprising a figure having arms, stub shafts journaled in the figure and to which the arms are secured, bevel gears fixed to the stub shaft, a rock shaft journaled on the figure, other bevel gears fixed to the rock shaft and meshing with the first mentioned gears, and a weighted member projecting from the rock shaft for actuating the latter to move the arms from lowered to raised position or vice versa according as the weighted member swings to one extreme position or another, at least one of said gears having its teeth mutilated at such location as to co-act with its mating gear in definitely limiting the extent to which the arms can be raised by said member.

3. A signaling device comprising a support having arms, stub shafts journaled in the support and to which the arms are secured, a rock shaft journaled on the support, gears operatively connecting the rock shaft with the stub shafts, a weighted member secured to the rock shaft, for actuating the latter to raise or lower the arms according as the weighted member swings to one extreme position or another, and means correlated with the gears to limit the extent to which the arms can be raised by said member.
